UNITED STATES PATENT OFFICE.

JOSEPH AUGUSTIN MALAISÉ, OF PARIS, FRANCE.

PROCESS OF UNHAIRING SKINS AND TRANSFERRING FUR, FEATHERS, HAIR, &c., TO ARTIFICIAL BACKINGS.

SPECIFICATION forming part of Letters Patent No. 639,075, dated December 12, 1899.

Application filed February 18, 1899. Serial No. 705,971. (No specimens.)

To all whom it may concern:

Be it known that I, JOSEPH AUGUSTIN MALAISÉ, of 45 Avenue de la République, in the city of Paris, Republic of France, have invented an Improved Process for Unhairing Skins and Transferring Fur, Feathers, Hair, and the Like to Artificial Backings, of which the following is a full, clear, and exact description.

10 This invention relates to a new and improved process for unhauling all kinds of skins without injuring the grain side thereof and also for transferring the fur, feathers, hair, bristles, wool, &c., to artificial backings.

15 The hitherto-employed methods for unhauling skins have been objectionable, because with such methods the hair is very often incompletely taken off, while the depilatory medium being immediately in contact with the grain side the latter, which constitutes the finest part of the leather, becomes injured and loses its fineness.

20 My improved unhauling process has for its object to entirely set aside these disadvantages and comprises the following operations:

All the hairs, feathers, and the like are treated with a solution forming a solid coat, in which all the hairs, feathers, &c., are held. This solution may consist of sodium sulfate.

30 When the solid coat is formed, I apply to the skin on the flesh side a depilatory paste of special composition. This paste or cream consists of a mixture of a solution of sulfide of sodium whose titration is lowered by

35 the addition of water to 5° or 8° Baumé, according to the nature of the skins to be treated, and of quicklime powdered by sprinkling of a certain proportion of water. The sulfide of sodium is mixed with the lime only

40 when the latter has previously been reduced into powder. I thus obtain a pasty mixture which can remain on the skin and whose active power is sufficient for taking off the hair from the skin without injuring in any way

45 the grain side of the latter. The pasty solution thus applied on the skin passes through the same and acts upon the root of the hair without injuring the grain side of the skin, so that the mass of hairs, feathers, and the

50 like confined in the sulfate of sodium may be readily stripped off. The skin, thus deprived of the fur, is then ready to receive any in-

dustrial application after having been subjected to the ordinary tanning operations. This depilatory paste possesses a very great 55 advantage, as it enables me to strip off all the hair, (hair, down, &c.,) and thus to use certain kinds of skins which have been hitherto incapable of any industrial application. Furthermore, with my process the unhauling proceeds more rapidly than with any other means.

After the hairs have been stripped off the roots thereof are covered with one or more coats of a caoutchouc solution in order to retain all these hairs. This fur can then be di-

rectly applied to a fabric such as cloth, silk, &c., it being sufficient to apply to the caoutchouc surface retaining the hairs a thin coat of a medium for dissolving the caoutchouc in order to obtain a perfect adhesion of the 70

caoutchouc upon the part intended to receive the fur. This part may even be impregnated with a caoutchouc solution. After such application has been effected the caoutchouc is vulcanized by any suitable means, so as to 75

obtain a perfect adhesion of the hair. This vulcanization will be effected according to any convenient method—for example, in the following manner: The objects will be hung in a hermetically-closed chamber whose in-

ternal temperature is carried to about 80° and into which vapors of chlorid of sulfur are led. The latter acting upon the caoutchouc will entirely vulcanize the same. The fur may also be applied upon an artificial 85

backing consisting of any flexible fabric, such as an unsized or undressed cotton material. The external face of the backing will also be covered with a coat of caoutchouc in such a manner that at the end of the process 90

it will be entirely embedded in the caoutchouc. The fur being thus fixed either im-

mediately on the fabric or on the artificial backing, it is now only necessary to dissolve the sulfate of sodium holding the hair for ter-

minating the process. The fur thus transferred may now be subjected to any dyeing process and be immersed in a boiling bath or in steam, because the vulcanized caoutchouc covering the fabric renders the same imper-

meable and does not permit of the hair being again stripped off from the same.

My improved process enables me to make use of hair which could not hitherto be em-

ployed as fur—such as calf-hair, for example—and also to dye such hair in any color. Furthermore, the fur thus obtained presents a perfect impermeability and may be employed 5 for numerous purposes.

My process also relates to natural furs treated according to the usual furriery processes the hair of which does not adhere to the skin for any reason—for example, when the 10 mites attack the roots of the hair. Under these circumstances the skin bearing such fur is previously untanned according to well-known processes, and the hair is then stripped off and transferred to an artificial backing, 15 according to above-specified means. A fur of any size composed of different pieces matched and put together may thus be transferred to an artificial backing in one piece. The fur thus transferred has the same appear- 20 ance and is arranged as the previous natural fur.

By means of my new process I can obtain furs of very large size either by directly transferring the hairs to a large surface of prepared fabric, as before described, or by putting together a certain number of furs transferred to an artificial backing, as above described.

My improved process enables me also to 30 make a new kind of artificial fur having hairs on both faces. This new kind of fur, therefore, consists of a backing of fabric embedded in caoutchouc and upon both faces of which are fixed the hairs removed from their skin,

as hereinbefore described. This new kind of 35 fur may also be obtained by omitting the fabric, whereby both coatings of caoutchouc holding the hairs are immediately connected together.

My process not only relates to the transfer 40 of hairs, but also to the transfer of feathers, bristles, and the like and generally of all kinds of dermic matters.

I claim—

The process of removing feathers, hairs and 45 the like from skins, which consists first in applying to the hair side of the skin, a coating of a substance to hold the hairs; second, in applying to the flesh side of the skin, a substance serving to penetrate the skin to facilitate removal of the hairs; third, in removing the hairs from the skin; fourth in coating the roots with rubber; fifth, in embedding a back- 50 ing in rubber; sixth, in connecting said back- ing with the rubber-coated face of the sub- 55 stance holding the hairs; and last in removing the substance in which the hairs are em- bedded.

The foregoing specification of my improved process for unhairing skins and transferring 60 fur, feathers, hairs, and the like to artificial backings signed by me this 3d day of Febru- ary, 1899.

JOSEPH AUGUSTIN MALAISE.
